UNITED STATES PATENT OFFICE.

EDWARD N. JACOBI, OF MILWAUKEE, WISCONSIN, ASSIGNOR TO BRIGGS & STRATTON COMPANY, OF MILWAUKEE, WISCONSIN, A CORPORATION OF WISCONSIN.

INSTRUMENT PANEL.

Application filed October 28, 1920. Serial No. 420,327.

To all whom it may concern:

Be it known that I, EDWARD N. JACOBI, a citizen of the United States, and resident of Milwaukee, in the county of Milwaukee and 5 State of Wisconsin, have invented new and useful Improvements in Instrument Panels, of which the following is a description, reference being had to the accompanying drawings, which are a part of this specification.

10 This invention relates to instrument panels, especially such as may be used on the instrument board of an automobile in which to mount lighting and ignition switches, ammeters and the like, and has for its object to 15 provide a firm support for the instruments, of neat and ornamental appearance and without visible attaching means.

Another object of the invention is to provide such a panel of thin sheet metal with a 20 heavier sheet metal clamp extending there-across as a bridge and containing the attaching means, said clamp engaging the edges of the panel to firmly clamp them against the instrument board.

25 With the above and other objects in view the invention consists in an instrument panel as herein claimed and all equivalents.

Referring to the accompanying drawings in which like characters of reference indicate the same parts in the different views:

Fig. 1 is a rear view of an instrument panel constructed in accordance with the present invention;

Fig. 2 is a transverse view thereof, partly 35 in section, showing the instrument panel mounted on an instrument board;

Fig. 3 is a sectional view of the end of the clamp on the plane of line 3—3 of Fig. 2; and

40 Fig. 4 is an end view of the clamping member.

In these drawings 10 indicates the thin sheet metal panel member having its edge bent to form a continuous rounding flange

45 11 to bear on the face of the instrument board 12. Openings 13 in the panel member are adapted to have instruments fitted thereto in any desired manner, and between these openings and extending across the panel from

50 one edge to the other is a clamp member 14, preferably consisting of a strip of heavier sheet metal. The clamp member is shaped to fit the sectional shape of the panel member, as seen in Fig. 2, with its ends turned

back to the plane of the edge of the panel 55 member where it is connected therewith. The connection is formed by tangs or ears 15 on the edge of the panel member 10 being bent through a notch 16 in the end of the clamp member 14 and clinched against the 60 inner face thereof. By reason of these tangs fitting against the ends of the notches in the ends of the clamp member they serve not only to hold the panel member securely on the clamp member but prevent all relative 65 movement between such members.

Near the bent ends of the clamp member where it is broadened there are depressions forming pockets 17 of a shape to receive and fit the flat-sided heads of screw studs 18, the 70 studs passing through openings in the bottom of the pockets and adapted to enter openings in the instrument board with nuts 19 threaded on their ends to draw the clamp member into clamping engagement with the 75 face of the instrument board. When the clamp member is thus clamped to the instrument board it holds the panel in place with a neat tight-fitting joint between the flange 80 of the panel member and the instrument board. The countersunk flat-sided heads of the studs prevent the studs from turning while the clamping nuts are threaded thereon and are completely hidden by the panel member. The panel member can be made of 85 thinner stock than would be feasible if ordinary connecting screws were used to attach it directly to the instrument board, for with the studs mounted on the heavier clamping member there is no danger of the clamp 90 connection dishing the panel member or drawing it out of shape. In other words, with this construction the clamping action is taken by the clamp member instead of the panel member. At the same time the panel 95 member is firmly held in place and constitutes a rigid support for the instruments.

Another advantage for the use of the clamp member with its securing studs, over the ordinary construction with exposed screw heads, is that the finished ornamental face of the panel member is not liable to be 100 scratched by slipping tools when clamping the panel in place.

What I claim as new and desire to secure 105 by Letters Patent is:

1. An instrument panel, comprising a thin sheet metal panel member, a heavier clamp

member extending across the back of the panel member, and attaching means carried by the clamp member.

2. An instrument panel, comprising a thin sheet metal panel member, a heavier clamp member on the back of the panel member with its ends connected with opposite edges of the panel member, and securing means mounted on the clamp member.

10 3. An instrument panel, comprising a thin sheet metal panel member having a bent surrounding flange, a clamp member on the back of the panel member correspondingly bent and connected with the opposite edges 15 of the panel member, and securing means on the clamp member.

4. An instrument panel comprising a thin sheet metal panel member having a surrounding flange, a clamp member on the back of the panel member with bent ends fitting within the flange and provided with recesses in their bearing edges, tangs on the flange bent through said recesses, and securing means mounted on the clamp member.

25 5. An instrument panel comprising a thin sheet metal panel member, a clamp member on the back thereof and secured thereto, screw studs passing through the clamp member and provided with flat-sided heads, and 30 pockets formed in the clamp member to receive the flat-sided heads of the screw studs and shaped to fit therewith.

6. An instrument panel for automobile panel boards and the like, comprising a thin sheet metal panel member having a bent surrounding flange to fit against the panel

board, a clamp member on the back of the panel member, and securing means on the clamp member for clamping it to the panel board, the edges of the panel member being 40 clamped between the clamp member and the panel board.

7. An instrument panel for mounting instruments on the panel board of an automobile or the like, comprising a panel member 45 of thin sheet metal with its edges bent to form a flange to bear on the panel board, and means for clamping the panel member to the panel board without dishing or distorting the panel member and comprising a 50 heavier clamp member extending across the panel member, clamping studs secured to the clamp member, and means for connecting the clamp member to the panel member.

8. An instrument panel for mounting instruments on the panel board of an automobile or the like, comprising a panel member 55 of thin sheet metal with its edges bent to form a flange to bear on the panel board, and means for clamping the panel member 60 to the panel board without dishing or distorting the panel member and comprising a heavier clamp member extending across the panel member, clamping studs secured to the clamp member, and means for connecting 65 the clamp member to the panel member comprising tangs on the edge of the flange of the panel member bent through recesses in the ends of the clamp member.

In testimony whereof, I affix my signature.

EDWARD N. JACOBI.
